UNITED STATES PATENT OFFICE.

JOHN E. BICKEL, OF PHILADELPHIA, PENNSYLVANIA.

SURF-MOTOR.

1,307,893.

Specification of Letters Patent. Patented June 24, 1919.

Application filed September 5, 1918. Serial No. 252,726.

To all whom it may concern:

Be it known that I, JOHN E. BICKEL, a citizen of the United States, residing at Philadelphia, in the county of Philadelphia and State of Pennsylvania, have invented a new and Improved Surf-Motor, of which the following is a specification.

My invention relates to that class of motor mechanisms in which is included a float 10 adapted to be lifted by the force of incoming waves or breakers and which furnishes the motive power.

Primarily, my invention has for its object to provide a relatively simple and inexpensive means of the wave motor type, that operates to automatically raise sufficient water to an elevated reservoir or tank, or a series of reservoirs or tanks, when my improved means is arranged in series, each of the said 20 means including a pump actuated by the impelling force derived from the waves or breakers coming on to shore, to thereby run turbine wheels, dynamos and other supplemental mechanisms adapted for ordinary 25 commercial uses.

Another and important object of my invention is to provide an improved construction of combined wave and surf actuated motor mechanism, in which the parts are 30 particularly designed for utilizing the force of breakers as they reach the shore line and which mechanism recedes from the shore line in such manner as it necessary to cover the varying distances of the breakers from the 35 shore, at high and low tides, and thereby provide, when my motor mechanisms are arranged in series, for maintaining pumping action of some of the said mechanisms at all times, while others may be idle.

40 Again, my invention seeks to provide an improved motor mechanism of the general type mentioned, in which the coöperating parts are so assembled as to provide against destruction under abnormal impelling forces 45 of the breakers and in which means is also included to permit the breakers to expand their surplus forces, the parts being also so designed whereby accumulation of sand around the pump intakes and the base of the 50 pump and float supporting framework is avoided.

With other objects in view, that will hereinafter appear, my invention embodies certain features of construction and novel combination of parts, all of which will be apparent from the following detailed descrip-

tion, as specifically outlined in the appended claims and as shown in the accompanying drawings, in which:

Figure 1 is a side view of my improved 60 construction of surf motor, the float being shown down and as being in a trough or break of the waves, parts being broken away to the more clearly illustrate the arrangement of the bottom or intake end of the 65 pumping mechanism.

Fig. 2 is a plan view thereof, parts being in horizontal section on the line 2—2 on Fig. 1.

Fig. 3 is a diagrammatic plan view that 70 illustrates an arrangement of an indefinite series of pumps mounted on a pile pier construction.

Fig. 4 is a longitudinal section, partly in side view, of a portion of the pump stock, the 75 pump piston, and a check valve construction.

Fig. 5 is a transverse section of the pump stock, the pump piston, the stay rods and the cap plate, see line 5—5 on Fig. 1.

In carrying out my invention, in its simplest form, the pumping mechanism is arranged substantially as shown in Fig. 1 in which is indicated a pier construction of pilings that supports the pier platform 25.

At a suitable point beneath the pier, a 85 base or bed 8 is provided preferably of concrete with sloping sides and ends to facilitate the off-throw of the sand, as the waves or breakers recede.

My improved motor mechanism, includes 90 a pump stock 4 on which is mounted, for substantially vertical reciprocation, a hollow float 9 which, in practice, may travel on ball bearings attached in any suitable manner to the float for riding on the stock 4. 95

In my construction of surf motor mechanism, I arrange the pump devices at an incline with respect to the shore line, the position of the pump stock and the piston elements being preferably at an angle of approximately 45 degrees to facilitate the rise and fall of the float member 9, as will presently be more fully explained.

An inclined support or beam 3 connects at the upper end to a sub-frame structure 26 105 built on the pier platform and which includes a cross head 27 that projects in a plane at right angles to the pump stock and which forms a bearing for the upper end of the said pump stock, as is clearly shown in 110 Fig. 1.

The lower end of the beam 3 is embedded

or otherwise made fast in the concrete base or bed 8.

11—11 designates stay rods and they are attached to the upper end of the float 9, are 5 guided in the cross head 27 and are joined at their extreme upper ends to a disk plate 16 that is fixedly secured on the upper end of the pump piston rod 10.

5 designates an outlet pipe which connects 10 with the upper end of the pump stock 4 and which, in practice, conveys the lifted fluid to the tank or other storage apartment.

17 designates the pump piston that carries a check, preferably a ball valve 13. 12 designates a stationary valve seat in the lower 15 end of the pump stock with which coöperates a ball check valve 18 which moves within the confines or cage members 19—19, as shown.

20 To the lower end of the pump stock, by means of an elbow joint 40, is secured a horizontal intake pipe 21 having a screen-like inflow head 6 and, when my pump mechanism is mounted on a concrete bed 8, 25 as is shown in Fig. 1, the pipe 21 is firmly clamped into position by sectional clamp brackets that are bolted to each other and are secured to a supplemental bed member 22 that is suitably anchored in the base or 30 concrete bed 8.

So far as described, it will be readily apparent, by reason of supporting the pump stock in the inclined position, the float 9 will be impelled under the force of the incoming waves in an upward direction, as indicated by the arrow α on Fig. 1, thereby providing for a comparatively free movement of the said float 9 along the pump stock under its wave impelled stroke and as it 40 drops down by gravity, as the wave recedes, it being understood that the up and down stroke of the float imparts the required power for actuating the pump mechanism.

As before noted, my improved motor 45 mechanism is especially designed for being operatively mounted along the shore line and for receiving the impelling power or forces of the waves as they become breakers approaching the shore.

50 For such purpose, the pump and pump operating float are located in an inclined trough or conduit whose main purpose is to concentrate the breakers or waves within the narrow confines, as they approach the float 55 to thereby direct the inwardly moving waves and breakers directly against the float and in such a manner that the maximum impelling forces are applied to the said float and in a direction that insures the desired 60 vertical lift thereof.

In the simplest form of my invention, the conduit or trough referred to consists of a sheet metal member 2 bent into a U shape, as is best shown in Figs. 1 and 2, from which 65 it will be also observed that the outer ends

20—20 of the member 2 are bent to form long sleeves 21'—21' for engaging vertical supports 30—30 whose lower ends are embedded in the base 8 and whose upper ends are made fast to the pier floor in any suitable manner. 70

The trough or conduit 2 is of a width to snugly fit over the opposite sides of the float 9, see Fig. 2, and the curved inner end 22 thereof is secured to the inclined supporting rim 3 by bolts and nuts 31—31, as shown. 75

When the conduit is formed as in Fig. 1, it is attached to its supporting members 3—30 with its bottom edge some distance 80 above the bed or base 8 to make provision for the easy outflow of the surf, as it recedes within the conduit and as the float lowers, and thereby also aids the out-wash of the sand and keeps the sand from banking over 85 the base 8 and the intake portion 6 of the pump.

It will be noticed, by again referring to Fig. 1, that the upper edge of the conduit 2 does not extend up to the pier floor, but is located a sufficient distance below the said 90 floor to permit the breakers or waves, that flow into the conduit under abnormal conditions, to expend their surplus forces by 95 breaking and escaping over the top edges of the conduit.

This latter feature of my invention is an essential one for the reason that unless provision is made for causing the abnormal wave or breaker forces to expend before the float is lifted to the limit of its upward movement, the float and the pump mechanism controlled thereby might be broken or displaced from a proper operative condition. 100

Since my motor mechanism is particularly adapted for utilizing the incoming surf or breakers along shore lines and since the said breakers always vary as to distances from the shore line, depending upon the tides, in the practical application of my invention, a plurality or series of my motor mechanisms are set up and, when the conduit is constructed as in Figs. 1 and 2, the 110 said mechanisms are arranged in longitudinal series, as diagrammatically illustrated in Fig. 3, it being understood that the pumping elements, when a series of such mechanisms is provided, as indicated in the 115 said diagram, may discharge the elevated water into a single or into a plurality of overhead tanks or containers. 120

From the foregoing description taken in connection with the accompanying drawings, the complete construction, the manner of operation, and the advantages of my improved surf motor mechanism will be readily apparent to those skilled in the art to which my invention relates. 125

While the drawings illustrate different 130

arrangements of my invention, it is to be understood that I do not restrict myself to the exact details described and shown, since they are subject to such changes that can be determined when the mechanism is to be operatively applied, *i. e.* the pitch of the pump to obtain the greatest impulse and get prompt gravity return and the dimensions of the pump and the float for effecting an efficient lift of water to the overhead storage tanks.

What I claim is:

1. A surf power mechanism, comprising a pump whose stock is supported inclined to the vertical, a float slideable on the stock, a connection between the float and the pump piston, and means for concentrating the inflowing wave or surf against the float, as it is being impelled upwardly, the said means comprising a conduit, the bottom of which inclines parallel with the inclined stock and whose sides extend rearwardly beyond the float and whose top is open, to thereby concentrate the incoming waves or surf forces against and around the float and allow abnormal inflowing waves or surf forces to expend themselves before the float reaches the limit of its lifted movement.

2. A surf power, comprising a pump mechanism, a float slideable along the pump cylinder, a connection between the said float and the pump piston, means for sustaining the pump mechanism at an incline to the vertical, and means for confining the incoming surf forces around and against the float, as it is being impelled by the said forces, the said means consisting of a U-shaped plate that constitutes a conduit in which the float travels in its up and down movement along the pumping cylinder and means for fixedly supporting the said plate.

3. A surf power, comprising a pump mechanism, a float slideable along the pump cylinder, a connection between the said float and the pump piston, means for sustaining the pump mechanism at an incline to the vertical, and means for confining the incoming surf forces around and against the float, as it is being impelled by the said forces, the said means consisting of a U-

shaped plate that constitutes a conduit in which the float travels in its up and down movement along the pumping cylinder and means for fixedly supporting the said plate, the lower edge of the said plate being located above the intake end of the pump, whereby to provide for the outflow at such end of the receding wave or surf forces.

4. A surf power, comprising a pump mechanism, a float slideable along the pump cylinder, a connection between the said float and the pump piston, means for sustaining the pump mechanism at an incline to the vertical, and means for confining the incoming surf forces around and against the float, as it is being impelled by the said forces, the said means consisting of a U-shaped plate that constitutes a conduit in which the float travels in its up and down movement along the pumping cylinder and means for fixedly supporting the said plate, the lower edge of the said plate being located above the intake end of the pump, whereby to provide for the outflow at such end of the receding wave or surf forces, and a bed having sloping sides and ends on which the intake end of the pump is mounted.

5. A surf power, comprising a pump mechanism, a float slideable along the pump cylinder, a connection between the said float and the pump piston, means for sustaining the pump mechanism at an incline to the vertical, and means for confining the incoming surf forces around and against the float, as it is being impelled by the said forces, the said means consisting of a U-shaped plate that constitutes a conduit in which the float travels in its up and down movement along the pumping cylinder and means for fixedly supporting the said plate, the lower edge of the said plate being located above the intake end of the pump, whereby to provide for the outflow at such end of the receding wave or surf forces, the upper end of the said plate terminating below the maximum float lift line, whereby to provide for expending the abnormal forces of the wave or surf before the float reaches the limit of its up thrust.
